UNITED STATES PATENT OFFICE.

SAMUEL C. TOWNSEND, OF BALTIMORE, MARYLAND.

DESIGN FOR A STRAW HAT.

SPECIFICATION forming part of Design No. 31,845, dated November 14, 1899.

Application filed August 28, 1899. Serial No. 728,801. Term of patent 3½ years.

To all whom it may concern:

Be it known that I, SAMUEL C. TOWNSEND, a citizen of the United States, residing at 211 West Fayette street, Baltimore city, State of Maryland, have invented and produced a new and original Design for Straw Hats, of which the following is a specification, reference being had to the accompanying drawing, forming part thereof.

10 The drawing shows a vertical elevation of a straw hat.

The leading feature of my design for a straw hat consists of the hard smooth edge interposed between the two layers of straw braids 15 of which the brim is composed.

1 is the hat-crown, 2 the brim, composed of an upper layer of braid 3 and a lower layer 4. 5 is the smooth edge, which projects beyond the edges of the upper and lower layer of braids of which the brim is formed and 20 creates the leading feature of my design.

What I claim is—

The design for a straw hat herein shown and described.

Signed by me at Baltimore city this 22d 25 day of July, 1899.

SAMUEL C. TOWNSEND.
